Charles A. Lindberg

UNITED STATES PATENT OFFICE.

CHARLES A. LINDBERG, OF STURGIS, MICHIGAN, ASSIGNOR TO STURGIS STEEL GO-CART CO., OF STURGIS, MICHIGAN, A CORPORATION OF MICHIGAN.

WHEEL-LOCK.

1,331,513.

Specification of Letters Patent. Patented Feb. 24, 1920.

Application filed August 30, 1919. Serial No. 320,904.

To all whom it may concern:

Be it known that I, CHARLES A. LINDBERG, a citizen of the United States, residing at Sturgis, county of St. Joseph, State 5 of Michigan, have invented certain new and useful Improvements in Wheel-Locks, of which the following is a specification.

This invention relates to improvements in wheel locks for children's carriages.

10 The main objects of this invention are to provide an improved wheel lock which is very secure, which may be easily engaged and disengaged, is inconspicuous and not likely to get out of repair.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated 25 in the accompanying drawing forming a part of this specification, in which:

Figure I is a detail rear view of a structure embodying the features of my invention, only such parts of a child's carriage, 30 being shown as seem desirable to illustrate an embodiment of my improvements.

Fig. II is a detail plan view of the parts shown in Fig. I.

Fig. III is a detail vertical section on a 35 line corresponding to line 3—3 of Fig. II, showing details of the actuating lever.

Fig. IV is a detail horizontal section on a line corresponding to line 4—4 of Fig. I and Fig. III.

40 Fig. V is a detail section on a line corresponding to line 5—5 of Fig. I showing structural details of the hub.

Fig. VI is a plan view of a blank from which the actuating lever is formed.

45 Fig. VII is a detail plan view showing a modified form or adaptation of my invention.

In the drawing similar reference characters refer to similar parts throughout the 50 several views, and the sectional views are taken looking in the direction of the little arrows at the end of the section lines.

Referring to the drawing, 1 represents the axle, 2 a wheel and 3 the running gear 55 frame of a child's carriage. I do not de-

scribe these parts in all details as such details form no part of my present invention.

The hub 4 of the wheel 2 is provided with an annular series of longitudinal bores 5, and with an end plate 6 having holes 7 60 therein registering to these bores. The end plate is secured by means of the screws 8. The locking rod 9 is mounted on the axle to engage these holes, and when so engaged, locks the wheel against rotation. In the embodiment illustrated the rod is supported by the axle clip 10 having lugs 11 projecting therefrom and through which the rod reciprocates. A coil spring 12 is arranged on the rod between these lugs with one end of the 70 spring engaging one lug and the other a thrust collar 13 on the rod, so that the rod is normally urged toward the hub.

The inner end of the rod engages the hole 14 and the actuating lever 15 which is 75 pivoted at 16 upon the rear side of the axle. The hole 14 is disposed relative to the lever pivot 16, so that by swinging the lever, the rod is projected or retracted to engage or disengage the hub. The lever is provided 80 with an arm 18 having a stop portion 19 on its upper edge adapted to engage the top of the axle, as illustrated, to limit the swing of the lever. The lever has an inturned portion 20, and the arm, being resilient, engages 85 the axle so that the lever is retained in its rod retracting position as shown in Fig. III.

The locking means may be conveniently engaged or disengaged by the foot of the operator, the lever being positioned on the 90 rear axle so that it is accessible. The portion 17, being turned rearwardly, may be easily engaged, a downward movement of the lever releasing the lock, and an upward movement thereof locking the same. 95

In the embodiment shown in Fig. VII, the locking rod 9 is supported by clip 21 having a single arm 22 through which the rod reciprocates. The rod is connected to the lever same as in the structure described. 100 The spring 23 in this embodiment is connected to the rod at 24 and to the frame at 25. This embodiment has the advantage of being somewhat simpler in structure. Its operation is, however, the same as that 105 shown in the other figures.

My improved lock is very simple and economical in structure. It is economically applied to the carriage or embodied therein, and strong and durable. 110

I have not attempted to illustrate certain other modifications and adaptations which might be desirable for different axle and running gear structures, as I believe the disclosure made will enable those skilled in the art to which my invention relates, to embody or adapt the same as may be desired.

Having thus described my invention, what I claim as new and desire to secure by Letters Patent is:

1. In a wheel locking device, the combination with an axle, of a wheel mounted thereon comprising a hub provided with an end plate at its inner end with an annular series of holes therein, a locking rod, a supporting clip mounted on said axle adjacent said wheel and having a pair of spaced lugs through which said locking rod reciprocates to engage with said hub holes, a spring arranged on said rod between said lugs, said rod being provided with a thrust collar with which one end of said spring engages, and a lever with which said rod is pivotally engaged, pivotally mounted on said axle, said lever being provided with a locking arm engaging the axle when the lever is in position to retract the locking rod.
2. In a wheel locking device, the combination with an axle, of a wheel mounted thereon comprising a hub provided with an annular series of holes, a locking rod, a supporting clip mounted on said axle adjacent and through which said locking rod reciprocates to engage with said hub holes, and a

lever with which said rod is pivotally engaged, pivotally mounted on said axle, said lever being provided with a locking arm engaging the axle when the lever is in position to retract the locking rod. 35

3. In a wheel locking device, the combination with an axle, of a wheel mounted thereon comprising a hub, a locking rod, a support on which said rod may be reciprocated to engage said hub, mounted on said axle, a spring arranged on said rod to engage said support, said rod being provided with a thrust collar with which one end of said spring engages, and an actuating lever for said rod pivotally mounted on said axle, said lever being provided with a locking arm 45 engaging the axle when the lever is in position to retract the locking rod. 50

4. In a wheel locking device, the combination with an axle, of a wheel mounted thereon comprising a hub, a locking rod, a support on which said rod may be reciprocated to engage said hub, and a lever to which said rod is connected pivotally mounted on said axle, said lever being provided with a locking arm engaging the axle when the lever is in position to retract the locking rod. 55

In witness whereof I have hereunto set my hand and seal in the presence of two witnesses.

CHARLES A. LINDBERG. [L. S.]
